DUAL POWER SUPPLY

Benjamin Shmurak, Lynbrook, Richard Projain, Jericho, Thomas Kelleher, Farmingdale, and Maurice G. Paulson, Huntington, N.Y., assignors to Lambda Electronics Corporation, Huntington, N.Y., a corporation of New York

Filed Aug. 8, 1968, Ser. No. 13,070

Term of patent 14 years

Int. Cl. D13—02

U.S. Cl. D26—15

FIG. 1

FIG. 2

FIG. 3

FIGURE 1 is an isometric view of a dual power supply embodying our new design;

FIGURE 2 is an isometric view of the dual power supply of FIGURE 1 illustrating same from the opposite side; and

FIGURE 3 is a perspective view of the dual power supply of FIGURES 1 and 2.

The dominant features of our design reside in the portions shown in full lines.

We claim:

The ornamental design for a dual power supply, as shown and described.
